UNITED STATES PATENT OFFICE.

SAMUEL SLADE, OF CHICAGO, ILLINOIS.

DIMMING ATTACHMENT FOR HEADLIGHTS.

1,380,916.

Specification of Letters Patent. Patented Feb. 17, 1920.

Application filed June 30, 1919. Serial No. 307,644.

To all whom it may concern:

Be it known that I, SAMUEL SLADE, a citizen of the United States, and a resident of Chicago, in the county of Cook and State of Illinois, have invented certain new and useful Improvements in Dimming Attachments for Headlights; and I do hereby declare that the following is a full, clear, and exact description thereof, reference being had to the accompanying drawings, and to the letters of reference marked thereon, which form a part of this specification.

This invention relates to dimming or non-glare attachments for headlights for automobiles and the like, and adjustable means for securing same to said headlight.

It has been proposed, heretofore, to use a strip of semi-transparent glass on the inside of and adjacent to the transparent lens or glass of a headlight and to attach the same to the inside of the headlight frame by means of metal plates, one secured at each end of the semi-transparent strip of glass. One of the difficulties attending such a device is that unless it is manufactured in standard sizes, the user, purchasing the device, is obliged to trim the thin metal plates to fit the annular groove and retaining rim of the headlight. The user may be more or less awkward in performing this operation and moreover, may not have the proper kind of shears at hand for the purpose; the result being that the non-glare or dimming device is frequently placed in the headlight improperly and because of this it does not do the intended work as efficiently as it should.

The principal object of my invention is to overcome this difficulty and to produce a semi-transparent or non-glare strip of glass provided with a metal attachment plate at each end, in such arrangement that it may be adjusted to fit the various sizes and shapes of headlight frames. This not only reduces the cost by enabling the manufacturer to make substantially but one size of the device for the market, but at the same time promotes the facility of the user in applying the device to the headlight.

In that form of my invention illustrated in the accompanying drawings,

Figure 1 is a vertical sectional view of a headlight to which my invention has been applied.

Fig. 2 is a front elevation of the same showing my invention installed in position.

Fig. 3 is a view, enlarged, of the metal blank unfolded which constitutes one of the metal attaching parts of the device.

Fig. 4 is a side elevation showing the blank folded and attached to one end of the semi-transparent plate of glass.

Fig. 5 is a side elevation of the same.

Fig. 6 is a transverse, sectional view of the same.

Fig. 7 is a similar view of a part of the device, showing a modification.

A represents the headlight as a whole and B the clear glass or lens thereof. Said headlight may be of any ordinary type, that illustrated comprising a metal frame 1, provided interiorly with a reflector 2 and a lamp 3. The end 4 of the frame is exteriorly screw threaded to receive an annular cap ring 5, the lens B being held in a familiar manner by the inturned flange 6 of the ring 5.

C designates a strip of semi-transparent glass which may be ground, etched, grooved or roughened on one face, as at 7, to produce the non-glare effect desired. This strip 7 is relatively narrow, as clearly shown in Fig. 2, and when in operative position in the headlight A, should stand diametrically across the center of the back of the lens B with the grooved or roughened surface 7 next to the back of the lens B and in the vertical position shown in Fig. 2, thus leaving on each side of the strip C a very considerable section of the transparent lens B.

In order that the strip C may be thus accurately positioned, I attach to each end thereof an extension or holding plate D, the outer rim 8 of which is cut on the arc of a circle of a diameter equal to the average diameter of the lamp lenses B now on the market. This plate D is made from the blank shown in Fig. 3 and comprises a main portion 9 having the rim 8 referred to and two laterally disposed arms 10, 10, near the outer end of which are apertures 11, 11. I may also provide and preferably do provide a second set of apertures 12, 12, outside of the apertures 11, 11, for the purpose hereinafter stated. This blank is made of thin sheet metal of a character easily folded and yet sufficiently rigid for its intended purpose. When it is desired to attach this plate to the non-glare glass C, I fold the strips 10, 10, at the points indicated by the dotted lines 13, 14, and fold the parts 10 over the glass C toward each other. Thus

the glass C is surrounded by the two parts 10, 10, the intermediate side walls 15, 15 and the lower part 16 of the blank.

In order to secure these folded arms 10, 10, together, I bend the outer ends 17, 17, thereof, at the points indicated at 18, 18, so that the parts 17 stand outwardly from the parts 10, and then insert a screw bolt 19 through the apertures 11, 11, thus pinching the parts or flanges 17, 17, together somewhat and causing the plate D to be firmly united to the glass strip C.

I find it to be a preferable construction, though not a necessary one, to fold the extreme outer ends 20 backwardly upon the outside faces of the ends 17, 17, before inserting the screw bolt 19; these parts 20, 20 thus acting in a sense as jam-nuts to more securely hold the screw bolt 19 in position. In positioning this non-glare strip C and the attached plates D, D, within the lamp A, if it is found that the extreme length of the device between the curved edges 8, 8, of the opposite plates, is greater than or less than the diameter of the lens B or space within the frame A, proper adjustment may be quickly made by loosening one or both of the screw bolts 19 and changing the relative position of the glass 25 C with respect to the plates D, as will be understood by reference to Fig. 4. In most cases, but one of the plates D will require adjustment.

Where but one adjustment is necessary, I may find it convenient to unite the two flange members 17, 17, by solder 21 or otherwise, as shown in the modification illustrated in Fig. 7. It is desirable, however, to have both plates D adjustable and to have the plates D extend or project approximately the same distance from the glass plate C.

I prefer to make the shape of the part 9 of the blank substantially as shown; that is to say, with an ogee curve 22 defining the laterally projecting parts 23. It is preferable, although not essential, that the plate D shall have the lateral projections 23 extending on each side of the plate C; that is to say, to have the transverse dimension of the plate D greater than the width of the strip C. I have stated that the plate D is a sheet of thin metal, but it may be

of any non-transparent material having sufficient rigidity for attaching purposes and yet sufficiently resilient and pliable to be bent as shown.

I claim as my invention:

1. As a new article of manufacture, a dimmer device for attachment to headlights comprising a thin, flat, relatively narrow strip of light absorbing material such as semi-transparent glass, a mounting plate secured to each end thereof, one of said plates being provided with laterally projecting arms adapted to be folded about the side margins and over the back of said strip, and secured together by a screw bolt. 65

2. As a new article of manufacture, a dimmer device for attachment to headlights comprising a thin, flat, relatively narrow strip of light absorbing material such as semi-transparent glass, a mounting plate secured to each end thereof, one of said plates being provided with laterally projecting arms adapted to be folded about the side margins and over the back of said strip, and secured together by a screw bolt, 75 the extreme ends of said folding arms being bent upon themselves to form a lock-nut or washer for said screw bolt. 80

3. As a new article of manufacture, a dimmer device for headlights, comprising a thin, flat, relatively narrow strip of light absorbing material provided at one end with 85 an adjustable mounting plate secured thereto by a screw bolt, said plate being made of a blank of sheet metal or other similar material having a straight lower edge or margin and a curved upper margin, and provided with laterally projecting arms, said arms being adapted to be folded along lines extending transversely of the arm, and an aperture through the end of each arm, the unfolded part of the blank being greater in 90 width or transverse dimension than the width of the light absorbing material to which it is attached. 95

In testimony that I claim the foregoing as my invention I affix my signature in the presence of two witnesses, this 21st day of June, A. D. 1919.

SAMUEL SLADE.
